UNITED STATES PATENT OFFICE.

CHARLES L. DEPOLLIER, OF BROOKLYN, NEW YORK.

DESIGN FOR A WATCHCASE.

SPECIFICATION forming part of Design No. 25,398, dated April 14, 1896.

Application filed January 9, 1896. Serial No. 574,913. Term of patent 7 years.

To all whom it may concern:

Be it known that I, CHARLES L. DEPOLLIER, a citizen of the United States, residing at Brooklyn, in the county of Kings, State of New York, have invented and produced a new and original Design for Watchcases, of which the following is a specification, reference being had to the accompanying drawings, showing a watchcase having my design applied thereto.

The leading feature of my design consists of a watchcase in which the lids or backs are concavo-convex in shape, although much flatter or more shallow than the lids or backs of ordinary cases, and from the lower rounding portion of which lids extends a raised bead, the case center upon which said backs rest or fit being flat or straight in cross-section, in contradistinction to being curved or outwardly bulged, thus giving to the case the combined effect of an ordinary and a box case.

Referring to the drawings, A is the watchcase center, which, in cross-section, is straight or flat, in contradistinction to being curved or outwardly bulged, as is ordinarily the case.

B B are the two lids or backs which, while they are concavo-convex in shape, yet are comparatively flat. Around the outer edge of these lids or backs B and at the point of meeting or joining the center A are raised beads C, which extend slightly beyond the case center, as clearly shown in Fig. 2.

Having fully described my invention, what I desire to secure by Design Letters Patent is—

The design for a watchcase as herein shown and described.
